UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

COMMODITY CABINET.

Application filed March 19, 1923. Serial No. 626,119.

This invention relates particularly to a commodity-cabinet of the type in which a rotary carrier is mounted in a casing, such cabinet being adapted to the purpose of 5 storing and vending small articles of merchandise, such as needles, shuttles and bobbins.

Cabinets of the general character set forth are now widely used throughout the country 10 by merchants for dispensing small articles of merchandise, and particularly sewing machine needles, bobbins and shuttles. There are in use throughout the country many sewing machines, known as stenciled machines, 15 which bear various names. The sizes, shapes and style of those parts and supplies which require rather frequent renewal, correspond, however, with a few primary makes of machines. It is the primary object of the present invention to provide improved means, 20 adapted to be applied to commodity-cabinets now in use, for enabling a needle or sewing machine part to be identified more easily with a primary make or manufacture, in order 25 that the required renewal or replacement part may be readily ascertained and supplied by the dealer.

The invention is illustrated in its preferred embodiment in the drawing, in 30 which—

Fig. 1 represents a plan view of a commodity-cabinet embodying the improvement; Fig. 2, a broken vertical sectional view taken as indicated at line 2 of Fig. 1; 35 and Fig. 3 a broken vertical sectional view taken as indicated at line 3 of Fig. 1.

In the construction illustrated, A represents the base-section of a casing; A', the cover-section of the casing; B, a central shaft journaled in the casing and having its upper end projecting through the top wall of the casing; C, a carrier disk fixedly mounted on the shaft B; D, an actuating member secured to the upper end of the 40 shaft B; E, a closure-plate associated with a radial hand-opening E' with which the top wall of the casing is provided; F, a locking-bolt which is actuated by a shank E² which extends inwardly from the inner end of the 45 closure-plate and is journaled on the shaft B; F', a locking-ring secured to the central portion of the carrier C; G, an annular series of dial numbers having the shaft B as a center, these numbers being preferably 50 printed or stamped on the wall of the cas-

ing; H, a separately formed dial plate through which the upper end of the shaft extends; I, a list of sewing machine names printed or lithographed on the top wall of the casing near the periphery; I', a series 60 of needle numbers associated with said names; and I², a series of bobbin and shuttle numbers associated with said names.

The casing-sections preferably are stamped or pressed from sheet metal, the flange of 65 the upper casing-section embracing and being supported on the flange of the lower casing-section. The actuating member D is secured to the upper end of the shaft B, by means of a pin 1. The central portion of 70 the disk of the cover-section A' is depressed, as indicated at 2, to accommodate the dial plate H. The series of numerals G may be printed or lithographed on the top disk of the casing-section A', adjacent the periphery of the dial plate.

The dial plate is provided with an annular series of presser-foot sockets, or presser-foot matrices, 3, and is provided also with a series of needle-prints 4, which may alternate to some extent with the presser-foot sockets. The dial plate H preferably is stamped from comparatively heavy sheet metal; and preferably the presser-foot 80 sockets 3 are formed by punching the metal 85 out by means of punches which correspond in shape with the shape of the presser-feet. The numerals of the dial-series G are closely associated with and correspond with the presser-foot sockets and the needle-prints. 90

The actuating arm D comprises a pointer 5 and a needle carrying arm 6, the arm 6 being provided with a matrix which is adapted to support a needle with the point portion projecting. Where the customer has a needle as a sample of what he desires, the needle may be placed in the matrix of the arm 6 and the carrier may then be rotated through the medium of the member D until the needle comes into correct registration 100 with one of the prints. The associated number of the dial-series G is the number assigned to the needle-tube for that size and style of needle. These needle-tubes (not shown) are so loaded on the carrier C that when the pointer arm 5 is turned to point to the numeral ascertained in the manner just mentioned, the proper needle-tube will be brought to a position beneath the hand-opening E. 105 110

Where the name of the sewing machine is known, the merchant may ascertain the number of the needle or part from the chart at I, I', I². When the customer does not know the name of the machine and where he has no sample needle, the presser-foot may be employed as a means for identifying the style and make of the needle or part. In such case, the presser-foot is tried in the various matrices until one is found which accurately receives the presser-foot. The associated radially disposed number of the dial-series G is the number assigned to the corresponding bobbins and shuttles, and in the illustration given, the number to the right, or clockwise, of the presser-foot socket is the number of the corresponding needle-tube. In the illustration given, the needle-tube numbers are also printed in the bottoms of the presser-foot matrices, as shown in Fig. 1. When the number desired is ascertained, either by reference to the chart at I, or by resorting to the expedient of placing a needle in the matrix of the arm 6 and rotating the carrier as described, or by the expedient of placing a presser-foot in its proper matrix, the pointer 5 may then be turned to point to the ascertained number appearing in the dial-series G. This brings the desired part beneath the hand-opening E', it being understood that the various sectors of the carrier C are loaded with the tubes or holders containing the appropriate needles and parts, the tubes or holders being so numbered and so disposed on the carrier that when the pointer 5 is turned to the desired number of the dial-series G, the proper part will be brought beneath the hand-opening E'.

By opening the closure E, access is had to the tube or holder which contains the desired needle or part.

The closure E is equipped at one of its inner corners with an actuating knob 7. When the closure is thrown to the open position, the locking-bolt F is thereby moved into locking engagement with the locking-ring F', so that the carrier cannot be rotated whenever the closure is in the open position. When the closure is moved to the closed position, the carrier is released. The movements of the locking-bolt F are effected by cam-connections with the shank E² of the closure E in a wellknown manner.

The dial plate H preferably is provided at

its central portion with an upwardly struck embossment 8 which is perforated to permit the shaft B to project therethrough. The lower surface of the hub portion of the actuating member B bears upon the embossment 8, tending to confine the dial plate H in its position in the depressed central portion of the casing-tube. The dial plate is provided at the front portion of its periphery with arms or projections 9 whose extremities are cupped upwardly, as indicated at 9^a. These cupped portions fit over the upper ends of rivets 10 (Fig. 3) which serve to secure to the top wall of the cover-section A' a marginal metal strip 11, which is disposed at the rear end of the hand-opening E'. The arms 9 thus serve as anchor arms which will prevent rotation or angular displacement of the dial plate H.

The foregoing detailed description has been given for clearness of understanding only, and no unnecessary limitations should be understood therefrom, but the appended claims should be construed as broadly as permissible in view of the prior art.

What I regard as new, and desire to secure by Letters Patent, is:

1. In combination in a commodity-cabinet, a casing having a sheet metal cover-section provided with a top wall having a depressed central portion, a dial plate accommodated by the depression at said central portion, said dial plate having anchor arms extending therefrom and engaging projections with which the top wall of the cover-section is equipped, a shaft extending through the top wall of the casing and through said dial plate, an actuating member secured to said shaft above said dial plate, and a carrier within said casing secured to said shaft.

2. In combination, a cabinet-casing having a sheet-metal cover-section provided with a top wall having a depressed central portion and having projections outside of the depressed portion, a dial-plate accommodated by the depression, said dial-plate having anchor arms extending therefrom and engaging said projections, a rotatable shaft extending through said top wall and dial-plate, and an actuating member secured to said shaft above said dial-plate and serving to hold the dial-plate in anchored position.

JAMES H. BOYE.
